UNITED STATES PATENT OFFICE.

MARC H. DAUDY, OF PHILADELPHIA, PENNSYLVANIA, ASSIGNOR TO NORTH AMERICAN LACE COMPANY, OF PHILADELPHIA, PENNSYLVANIA, A CORPORATION OF PENNSYLVANIA.

DESIGN FOR LACE.

Application filed May 8, 1926. Serial No. 17,616. Term of patent 3½ years.

To all whom it may concern:

Be it known that I, MARC H. DAUDY, a citizen of the Republic of France, residing at Philadelphia, Pennsylvania, have invented a new, original, and ornamental Design for Lace, of which the following is a specification, reference being had to the accompanying drawing, in which:

The figure is a face view of a piece of lace illustrating my new design.

The essential feature of the design is the solid strip of compact lace extending between two strips of open lace, the color of the solid strip contrasting with the color of the strips of open lace.

I claim:

The ornamental design for lace, substantially as shown and described.

MARC H. DAUDY.
